UNITED STATES PATENT OFFICE.

HERMANN LEMP, OF LYNN, MASSACHUSETTS, ASSIGNOR, BY MESNE ASSIGNMENTS, TO
GENERAL ELECTRIC COMPANY, A CORPORATION OF NEW YORK.

STEAM-GENERATOR.

No. 859,305.

Specification of Letters Patent.

Patented July 9, 1907.

Application filed February 28, 1900. Serial No. 6,805.

To all whom it may concern:

Be it known that I, HERMANN LEMP, a citizen of the United States, residing at Lynn, county of Essex, State of Massachusetts, have invented certain new and useful Improvements in Steam-Generators, of which the following is a specification.

Attempts have been made heretofore to utilize generators or boilers for the rapid production of steam in automobiles, but without any substantial or permanent success, owing principally to the use of screw threaded unions for connecting the several sections of which the boiler was composed. It is not practical to make these boilers out of a single piece of tubing, owing to mechanical difficulties in the process of construction, and for that reason when commercially produced, they have been made up of sections, and some form of joint employed between the sections. In boilers for such rapid generation of steam a comparatively small quantity of water is admitted at a time, which water is converted into steam at some point during its passage through the hot pipes, a suitable flame being employed to heat the pipes. In this way the pipes are subjected to alternate heating and cooling, which although not materially affecting the pipes or tubes soon causes the unions to leak and thereby renders the boiler useless.

I overcome the objections above pointed out by making the boiler in sections and electrically welding the sections together so that for all practical purposes the boiler is composed of an endless tube. When the joints are properly made it has been shown by careful tests that the tubes are as strong at the joints as at any other point. These joints are situated directly in the path of the hot gases from the burner and no effort is made to protect them in any way. Furthermore the sections of the boiler have been so designed that the bending can be accomplished in a simple bending machine, and each section is like every other. The construction of these sections as well as their relation to each other, and the consequent advantages thereof are more fully described and claimed hereinafter.

In the accompanying drawings which illustrate my invention, Figure 1 is a vertical section of the boiler and burner; Fig. 2 is a partial vertical section of a boiler taken on line 5, 5 of Fig. 1, looking in the direction of the arrow; Fig. 3 is a plan view of the boiler with the top removed; Fig. 4 is a detail plan view of one of the boiler grids as it appears before being welded to the other grids; Fig. 5 shows the preferred manner of connecting the boiler sections; Figs. 6 and 7 show diagrammatic illustrations of boiler connections made for the purpose of comparison; Fig. 8 is a plan view of a boiler constructed on a slightly modified plan; and Fig. 9 is a cross-section of the boiler taken on line 16, 16 of Fig. 8.

The boiler or generator is composed of a series of

grids I made up of seamless tubing of small bore but large cross section and shaped as shown in Fig. 4. The grids may be bent into any suitable form, providing that when they are assembled spaces or flues will be formed permitting the products of combustion to pass freely between the bottom and top, or between the sides providing it is desired to operate the boiler in that way. The form of grid shown in the drawing is one of the best on account of its simplicity since it can be made in an ordinary bending machine, and at the same time is readily handled in an electric welding machine of the well-known Thomson type. Two ends or terminals I¹ and I² of substantially equal length are provided for each grid, the end or terminal I¹ extending in the general direction of the turns in the grid while the end or terminal I² is at right angles thereto, in other words the ends extend toward a common point. The turns of the grid lie in a common plane while the terminals extend at a greater or less angle to the common plane of the turns and on opposite sides thereof. This feature in the construction permits of the several grids being welded together without the addition of connecting pieces of any sort and without making sharp bends in the ends or terminals I¹ and I².

Assuming that a number of grids have been made and it is desired to assemble them, two grids are mounted in the welding clamps in such manner that end I¹ of one is in juxtaposition to end I² of the other; this means that the tubes I³ of the second grid instead of being parallel with those of the first grid are at right angles thereto, thus forming a series of substantially square openings or flues through which the products of combustion may pass. The second grid having been revolved through an angular distance of 90 degrees, the weld between end I² of the second grid, and end I¹ of the third grid will be at point I⁴, Fig. 3; and the next weld at I⁵, and so on, thus making a series of welds each angularly displaced from the other by approximately 90 degrees in a clockwise direction, or by a like amount in an anti-clockwise direction if the welding is started in the opposite direction.

Referring to the sectional views, Figs. 1 and 2, it will be seen that vertical spaces are left between the tubes through which the products of combustion pass, that the grids occupy parallel planes, and that the position of every fourth grid is like the first, in other words the joints have made a cycle and are at the position of starting.

All of the joints between the sections are subjected to the furnace flame, and no attempt is made to protect them. On account of this feature of the construction I am enabled to manufacture and sell to the user a boiler which can readily be mounted in the casing, and one which requires that only two joints shall be made, and these at the extreme ends. The old boiler

can be removed and a new one readily substituted by anyone of ordinary average intelligence.

Surrounding the boiler tube is metal casing J, and between the casing and the tube is located a packing 5 of heat resisting material J¹, as asbestos for example. Bolted to the inside of the casing is a frame piece J² on which rests the asbestos and two tubes J³, the latter being employed to support the boiler tube but not to assist in making steam. Connection between the engine, and water tank and the boiler tube is made at 10 the ends, which ends may be located at the top and bottom of the mass of tubes or at intermediate points as will be hereinafter described. In any event the construction should be such that the boiler tube can expand or contract without straining the connections. 15 With the parts arranged as shown each grid is capable of moving independently, to a limited extent, of every other grid in the boiler, and no matter how rapidly the temperature changes take place they are always 20 compensated for. Again, the boiler tube, on account of its not being secured rigidly to the vehicle frame, is not subjected to strains due to obstructions in the road.

In the drawings, the tubes forming the grids are 25 shown as circular in cross-section, but tubes of any other cross-section may be substituted therefor. The top of the boiler has a cover K and is provided with flues K³ and K⁴.

Situated under the boiler is the fire-box or chamber 30 D. As here shown the casing which surrounds the boiler performs the same office for the fire box, but if desired a separate casing may be employed and the two joined together. The fire box is substantially square, and located within the box and surrounding the burner 35 is a circular coil of pipe D³ for heating the feed water as it passes from the water tank to the boiler. The feed water pipe is connected to the upper end of the boiler by an external connection D⁴, and by reason of its being located outside of the casing screw-threaded 40 couplings can be employed. Located between the casing and the pipe is a packing D¹ of heat resisting material, which is supported by a frame piece D² that also acts to support the coil of pipe.

Referring to Figs. 5, 6 and 7 three different forms of 45 boiler connections are shown. In Fig. 6 the feed water enters at the upper end and passes toward the bottom, leaving the lower end as superheated steam; this same form of connection is shown in Fig. 1. This is a desirable arrangement since it is very economical in the 50 production of steam and the latter leaves the boiler at the very hottest point. It is objectionable, however, in that it subjects the boiler tube to very great strain.

Fig. 7 shows a boiler in which the feed water enters 55 at the tube where the flames are the hottest and the superheated steam leaves the pipe where the flames are considerably cooler having had a good deal of energy absorbed by the tubes in the upward passage. This has the advantage of giving a long life to the tubes, but is not so satisfactory with regards the production of 60 steam, and is apt to cause water to be entrained.

In Fig. 5 I have shown a modification in which 65 the advantages of the two boilers previously described are combined, and the disadvantages are minimized. Water enters the tube at the top and after passing through about one-half of the total length of the tube

a connection I¹ is made to the lower end of the boiler, the water or steam or both then pass upward and the superheated steam leaves the boiler by pipe I². In the drawing, four grids or sections are shown as being connected so that the passage of steam and water is in 70 one direction, and four so that they are in the opposite direction, but I may connect more grids in one section than in another as desired. With the arrangement shown water enters the tube at its coolest point, and after it has become heated to a greater or less extent it 75 passes to the lowest grid or layer of tubes where the flames are the hottest. On account of the ability of the water at this point to absorb heat, the tubes do not get as hot as in Fig. 6. Between the top and bottom of the boiler there is of course a difference in the temperature 80 of the fire gases, but by taking steam at the point shown no particular difference in the character of the steam is noticed, and the tubes have a long life.

In Figs. 8 and 9 a boiler is shown which is composed 85 of grids or sections welded together, but the relation of the grids differs slightly from that previously described. Each grid is composed of a series of parallel tubes I³ connected by curved ends. Each grid is made out of a single piece of tubing bent back and forth on itself. The grids are electrically welded in the manner previously described, but the disposition one on top of the other has been slightly altered. The space between the parallel tubes I³ is made as small as the bending of the tubes will permit, and by placing the grids one over the other as shown, that is to say with 90 the tubes of one grid midway between the tubes of the grid above and below it, the vertical chambers or passages I⁶ are smaller than when the tubes are disposed one directly over the other. This arrangement tends to baffle or spread the flames more than in the first described construction.

The subject matter described and not claimed in this application will be found in my divisional applications bearing the following serial numbers: 35,254, filed Nov. 2, 1900, 45,028, filed Jan. 28, 1901, and 105 46,313, filed Feb. 7, 1901.

In accordance with the provisions of the patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States is,

1. As an article of manufacture, a grid for a boiler, comprising a single piece of tube bent back and forth on itself, with terminals or end connections which extend toward a common point.

2. A steam generator composed of a series of grids, each grid comprising a single piece of tubing bent back and forth on itself, the tubes forming one grid being located angularly with respect to the tubes forming another grid, and the intermediate grids being provided with ends or terminals of a length less than that of the grids, and which are so arranged that one of them is welded to an upper grid and the other to a lower grid.

3. In a steam generator the combination of a plurality of tubular grids, each grid having two ends or terminals which extend toward a common point, with electrically welded joints between the ends of the grids.

4. As an article of manufacture, a steam generator comprising a plurality of counterpart grids the alternate

grids of which are similarly disposed, each grid being composed of a piece of tubing bent back and forth on itself, with terminals which occupy positions substantially at right angles to each other; and means for uniting 5 the terminals.

5. As an article of manufacture, a steam generator composed of a plurality of counterpart grids, piled one on the other, each grid having two ends or terminals extending toward a common point, and electrically welded joints 10 between the ends of the several grids, the said joints making an angular progression with respect to a common center.

6. As an article of manufacture, a boiler composed of a plurality of grids, each grid being composed of parallel 15 tubes I^1 and ends or terminals I^1 I^2 which extend substantially at right angles to each other, the end I^1 of one section being welded to the end I^2 of a second section.

7. As an article of manufacture, a grid for a steam generator comprising a single piece of tubing bent back 20 and forth to form a steam generating device and having two free ends, one end being substantially parallel with the main portions of the tube, and the other at substantially right angles thereto.

8. A steam generator composed of sections which rest 25 upon one another, each section composed of a number of grids which rest on each other, each grid being capable of a slight movement independent of the other or others, and a connection between one section and the other.

9. As an article of manufacture, a boiler composed of 30 sections, each section being made up of a coil of tubing, and a connection which extends from the inside end of one section across the outside of the body of the second section, to its outside end.

10. As an article of manufacture, a grid for a steam 35 generator, comprising a single piece of tubing having straight portions which are connected by curved end portions, with two terminal connections, one of which extends substantially parallel with the straight portion of the tube, while the other extends substantially at right 40 angles thereto.

11. As an article of manufacture, a section for a steam generator, comprising a continuous piece of tubing bent back and forth to form a substantially rectangular grid, with terminals which have a length equal to half that of 45 the grid.

12. As an article of manufacture, a boiler comprising a plurality of counterpart grids of which every fourth one is positioned like the first, each grid being provided with terminals extending substantially at right angles to 50 each other, the tubes of the adjacent grids occupying positions at right angles to each other, and joints between the grids.

13. As an article of manufacture, a boiler comprising a coil of tubing divided into sections, each section comprising a plurality of connected grids, each having a long and a short end connection, a connection for conveying 55 liquid into one of the coil sections at its coolest point, a

connection which unites the hottest portion of said coil with the hottest portion of another section, and a connection for conveying vapor from the coolest portion of 60 the last-mentioned section.

14. The combination of a burner, a feed water coil adjacent thereto in which the flow is in the direction of the fire gases, a steam generating coil superposed with respect to the burner in which the flow is counter to the fire 65 gases, a superheating coil connected with the generating coil in which the flow is in the direction of the fire gases, a casing for the coils and burner, and a connection between the generating coil and feed water coil which is exterior to the casing. 70

15. A grid for a boiler, comprising a tube coiled back and forth on itself several times and terminating mid-way of the sides of the grid.

16. A grid for a boiler, comprising a tube coiled back and forth on itself a number of times and terminating mid-way of two adjacent sides of the grid. 75

17. A grid for a boiler, comprising a tube coiled back upon itself several times in a common plane and having terminals which end mid-way of two sides of the grid and extend at an angle on opposite sides of the grid. 80

18. A grid for a boiler, comprising a coiled tube having its ends located at the outside of the grid, one end extending at a slight angle above the general plane of the grid, and the other extending at a slight angle below said plane, one end terminating near the middle of one side of said 85 grid, and the other near the middle of an adjacent side thereof.

19. A boiler composed of a plurality of grids each comprising a coiled tube with both of its ends located at the outside thereof, one end extending at a slight angle above 90 the general plane of the grid, and the other extending at a slight angle below said plane, said ends terminating near the middle of adjacent sides of the grid, and connections between adjacent ends of adjacent grids.

20. A boiler comprising a plurality of similar rectangular grids, each composed of a coiled tube whose ends terminate at two sides thereof at points intermediate adjacent corners, the grids being so formed that when two or more have their ends connected, the lengths of tube in each grid are arranged substantially at right angles to those in the 100 immediately adjacent grids. 95

21. A steam generator composed of grids, each grid formed from a single piece of tubing bent back and forth on itself with its terminals extending toward a common point, and connections between the terminals of adjacent 105 grids which join the grids in a continuous superposed series.

In witness whereof I have hereunto set my hand this 26th day of February, 1900.

HERMANN LEMP.
